CLAIM

The ornamental design for an air-conditioner, as shown and described.

DESCRIPTION

FIG. 1 is a front, bottom and right side perspective view of a air-conditioner showing our new design; FIG. 2 is a front elevational view thereof; FIG. 3 is a top plan view thereof; FIG. 4 is a bottom plan view thereof; FIG. 5 is a left side elevational view thereof; FIG. 6 is a right side elevational view thereof; FIG. 7 is a rear elevational view thereof; and FIG. 8 is a front, bottom and right side perspective view thereof, with the air deflect panel shown in an alternate position; and FIG. 9 is an enlarged vertical cross-sectional view thereof, taken along line 9—9 of FIG. 2.

FIG. 1
